UNITED STATES PATENT OFFICE.

FRIEDRICH RICH. BACHLER, OF OXNARD, CALIFORNIA.

DILATING-BOUGIE.

SPECIFICATION forming part of Letters Patent No. 734,498, dated July 28, 1903.

Application filed October 20, 1902. Serial No. 127,981. (No model.)

To all whom it may concern:

Be it known that I, FRIEDRICH RICH. BACHLER, a subject of the Emperor of Austria-Hungary, residing at Oxnard, in the county of 5 Ventura and State of California, have invented new and useful Improvements in Dilating Sounds or Bougies, of which the following is a specification.

My invention is designed for the production of an improved dilating sound or bougie, the object of the same being to provide a novel construction of instrument of this kind, which is adapted to be laterally expanded at one or more points for use in dilating or 15 stretching the urethra for the cure of strictures.

My improved sound consists of a flexible tube constructed of vulcanized rubber or the like having a smooth unobstructed outer surface and having a bore of two different diameters, the inner surface of the tube surrounding that part of the bore of smaller diameter being lined with a suitable inelastic fabric and that portion of the tube which 25 incloses the part of the bore of larger diameter being of highly-flexible rubber, the said tube being provided with means for the introduction of air under pressure to the interior thereof.

30 The invention also consists of certain features and details of construction and combinations of parts, which will be hereinafter more fully described and claimed.

In the drawings forming a part of this specification, Figure 1 is a longitudinal section of a sound or bougie constructed in accordance with my invention, showing the same in its normal condition; and Fig. 2 is a similar view of the same, showing the elastic portion 40 thereof laterally expanded.

My improved sound or bougie consists of a tube 1, of vulcanized rubber or other suitable flexible material, having a smooth unobstructed outer surface throughout and provided with screw-threads 2 at one end thereof for the convenient attachment of a rubber bulb 3 for the introduction of air under pressure to the interior of said tube. The head 4 of the tube 1 is rounded on its end and the 45 bore of said tube, which extends partially into the head 4, is made of two different diameters,

(indicated, respectively, by the reference-numerals 5 and 6.) That portion of the tube 1 which surrounds the narrow or contracted part 5 of the bore therethrough is lined with 55 inelastic fabric 7, whereas the portion 8 of the tube 1 which surrounds the part 6 of the bore of larger diameter is unlined and is made of elastic rubber. The result of this construction is that while the bougie or sound as a 60 whole is flexible it is inelastic, except at a point between the head 4 and the main body of the tube 1, where it is highly elastic. The thickened walls of the tube, which surround the contracted portion 5 of the central bore 65 therethrough, and the inelastic fabric 7 serve to prevent the stretching or lateral expansion of the tube, whereas the elastic portion 8 of the tube renders the same very expansible from pressure applied from within. 70

In using my improved sound or bougie the same is introduced in the usual manner into the urethral passage until the elastic portion thereof reaches a point just opposite the stricture or other affected part to be treated. The 75 bulb 3 is then compressed, with the result that air under pressure is forced through the central bore or passage in the tube 1 and serves to expand the elastic portion 8 of said tube. The stricture may thus be dilated without 80 the necessity of using sounds or bougies of different sizes. The pressure applied may be readily regulated by the patient himself by an increase or decrease in the compression of the bulb 3, and consequently the pain to 85 which the patient is subjected may be reduced to a minimum.

The tube 1 may be made in different diameters and lengths and may of course be supplied with internal pressure by other means 90 than the bulb 3. I prefer, however, to use a compressible bulb, and accordingly all of the sounds or bougies in a set will be provided with screw-threads 2 of the same size, so that a single bulb 3 may be applied to any one of 95 the same.

Having now described my invention, what I claim as new, and desire to secure by Letters Patent, is—

1. A hollow flexible sound or bougie having a bore therein of different diameters, the thin portion of said sound surrounding that

portion of the bore of larger diameter being elastic, and means for applying internal pneumatic pressure within said sound.

2. A hollow flexible sound or bougie having a closed head and a smooth unobstructed exterior surface, and having the bore therein of different diameters, the thin portion of the sound which surrounds the enlarged portion of said bore being elastic and the remaining portion of said sound being inelastic, and means for applying internal pneumatic pressure within said sound.

3. A hollow flexible sound or bougie having a closed head and a smooth unobstructed exterior surface, and having the bore therein of different diameters, the thin portion of said sound which surrounds the enlarged portion of said bore being elastic, a lining of in-

elastic fabric for the contracted portion of said bore, and means for applying internal pneumatic pressure within said sound.

4. A hollow flexible sound or bougie having a closed head, a bore of different diameters therein and screw-threads upon the end thereof opposite said head, the thin portion of said sound which surrounds the enlarged portion of said bore being elastic, and a rubber bulb having screw-threads thereon adapted to engage the screw-threads on said sound.

In testimony whereof I have hereunto set my hand in presence of two subscribing witnesses.

FRIED. RICH. BACHLER.
